CONSOLE STRUCTURE FOR INDUCTION HEATING

Otto Kreisel, Haledon, N. J.

Application April 14, 1954, Serial No. 30,020

Term of patent 14 years

(Cl. D26—5)

Fig. 1

Fig. 2

*Fig. 3**Fig. 4*Figure 1 is a front perspective view of a console structure for induction heating, showing my new design;

Figure 2 is a rear elevational view;

Figure 3 is an end elevational view, looking at the left of Figure 1; and

Figure 4 is an end elevational view taken from the opposite end.

I claim:

The ornamental design for a console structure for induction heating, as shown.
